SPRING PLANK

Ralph B. Winship, Montreal, Quebec, Canada

Application September 14, 1933, Serial No. 689,406

6 Claims. (Cl. 105—208.2)

This invention relates to spring planks for car trucks.

The spring planks most commonly used in car trucks today are of rigid construction from one end to the other, and as strains and stresses are imposed upon the spring plank, due to the adjustment of the truck to various track conditions, the rigidity of the spring plank will not allow it to take the strains and stresses without danger of breakage.

It is accordingly an object of the present invention to provide a spring plank of novel and improved construction having sufficient resiliency to take the strains and stresses imposed thereon without danger of breakage.

The objects and advantages of the invention will more fully appear from the following description, made in connection with the accompanying drawings, wherein like reference characters refer to the same or similar parts throughout the various views, and, in which,

Fig. 1 is a view in side elevation showing a portion of a side frame of a car truck with a spring plank embodying the invention applied thereto;

Fig. 2 is a vertical transverse section taken on the line 2—2 of Fig. 1, as indicated by the arrows;

Fig. 3 is a view looking toward one edge of the spring plank shown in Figs. 1 and 2;

Fig. 4 is a detailed view in enlarged scale showing in plan one end of the spring plank shown in Figs. 1 to 3;

Fig. 5 is a vertical section taken on the line 5—5 of Fig. 2, as indicated by the arrows;

Fig. 6 is a view illustrating in plan one end of a modified form of spring plank embodying the invention;

Fig. 7 is a vertical section taken on the line 7—7 of Fig. 6, as indicated by the arrows;

Fig. 8 is a view looking toward one edge of a third modified form of the invention, certain parts being broken away to more clearly show the construction thereof;

Fig. 9 is a vertical section taken on the line 9—9 of Fig. 8, as indicated by the arrows; and

Figs. 10 and 11 are vertical sectional views taken in the same manner as are Figs. 5 and 7 through the central portions of two other modifications of the invention.

Referring first to the embodiment of the invention illustrated in Figs. 1 to 5 inclusive, there are shown portions of a side frame 12 of a car truck. This side frame includes the usual columns 12a and a tension member 12b having diagonal ribs 12c projecting diagonally upwardly

from the spring plank seat adjacent and joining the columns 12a.

In accordance with the invention there is provided a spring plank A which runs between the opposed side frames 12 of the truck and rests at its end portions 13 on the tension members 12b of the side frames between the columns 12a thereof. The spring plank A like every other modified form of the invention is provided with an elongated central rigid portion 14, end portions 13 resting on the side frames and flat resilient portions 15 joining the central rigid portion to the end portions. The elongated central portion of the particular spring plank A shown is made rigid by providing a central comparatively wide upwardly pressed channel 16 and two narrower upwardly pressed channels 17 laterally spaced respectively from the channels 16 in this elongated central portion of the spring plank. The channels 16 and 17 terminate where the central portion 14 joins the resilient portions 15 and these resilient portions are absolutely flat throughout the width of the plank. To retain the end portions 13 of the spring plank A in place on the side frames, so as to permit of but very slight lateral motion of the spring plank relative to the two side frames, the spring plank is provided with downwardly pressed cupped portions 18 adjacent the inner edges of the side frames and downwardly projecting arcuate flanges 19 adjacent the outer edges of the side frames. Also for this same purpose and to fit the particular side frame 12 shown, the end portions 13 of the spring plank A are provided with diagonally, upwardly extending channels 20 within which the ribs 12c are received.

Referring now to the embodiment of the invention illustrated in Figs. 6 and 7, the spring plank B there shown like the spring plank A, is provided with an elongated central rigid portion 14, end portions 13 adapted to be received on the side frames, and flat resilient portions 15 joining the elongated central rigid portions to the end portions. The central elongated portion is made rigid by three longitudinally extending upwardly projecting channels 21 and 22 respectively. To hold the end portions 13 of the spring plank B in place on the side frames, dowel pin openings 23 are provided in these end portions through which dowel pins (not illustrated) 50 mounted on the tension members of the side frames may extend.

Referring now to the embodiment of the invention illustrated in Figs. 8 and 9, there is shown a spring plank C which, like the others, has a

central elongated rigid portion 14, end portions 13 adapted to rest on the side frames and flat resilient portions 15 connecting the central portion with the end portions. The spring plank C shown is of general channel construction and is provided with upwardly extending edge flanges 24, which are cut away to form notches 25 at the edges of the resilient portions 15. The end portions 13 of the spring plank C may be provided 10 with any suitable means so that they will hold their positions on the side frames such as the dowel pin openings 26 illustrated.

To show that various means may be used for making the central elongated portion of the 15 spring plank rigid without departing from the scope of the invention, Figs. 10 and 11 are shown. In Fig. 10, a spring plank D is provided having an elongated central rigid portion 14 provided with other types of upwardly pressed channels 27 and 28 than those in the other planks. The elongated central portion 14 of the spring plank E shown in Fig. 11, is made rigid by alternate upwardly and downwardly pressed V-shaped channels 29 and 30 respectively. It will 25 be appreciated that there are many other means that may be used for making the elongated central portion of the spring plank rigid. It will also be appreciated that it is possible to equip the end portions 13 of the spring planks with means 30 for preventing other than very limited lateral movement of the spring planks relative to the side frames, different from the means shown, and these means may be adapted for use with any type of side frame without departing from the 35 scope of the invention.

When any one of the spring planks is in use, the resilient portions 15 joining the elongated central rigid portion 14 to the end portions 13 will take the strains and stresses imposed on the 40 spring plank due to variations in track conditions as the truck rides over the rails. As the portions 15 have considerable resiliency, the spring plank can flex at these portions thereof without danger of breakage, so as to allow either end portion 13 to move relative to the elongated central rigid portion 14 and with respect to the other end portion 13 without stressing the spring plank beyond its elastic limit. The elongated central portion of the spring plank is made rigid as by channels, ribs, flanges or the like, to stiffen the spring plank and take care of the column action of the truck or vibrations. It is quite desirable to make the spring plank as simple, light and strong as 45 possible to secure all the advantages of the invention and for this reason the elongated central portion of the spring plank will preferably be made of quite thin material, flanged, grooved, corrugated or channeled to give it the proper 50 rigidity. It will of course, be appreciated that if desired, the elongated central portion of the plank can be made of heavier stock than the resilient portions 15, without channeling, flanging,

grooving or corrugating the central portion, to accomplish the same result.

It will be seen that a strong, durable spring plank has been provided which can be effectively used. 5

It will, of course, be understood that various changes may be made in the form, details, arrangement and proportions of the various parts without departing from the scope of the present invention, which, generally stated, consists in the 10 matter shown and described and set forth in the appended claims.

What is claimed is:—

1. A spring plank for car trucks having an elongated central rigid portion, end portions 15 adapted to rest on side frames, and flat portions joining the central portion to the end portions, said flat portions being resilient.

2. A spring plank for car trucks having an elongated central rigid portion, end portions adapted 20 to rest on the side frame and resilient portions joining the central portion to the end portions, said end portions being equipped with means for engaging the side frames to prevent other than very limited lateral motion of the spring plank 25 relative to the side frames, said means comprising deformations in said end portions adapted to engage with projections on the side frames.

3. A spring plank for car trucks having an elongated central portion made rigid by ribs, end 30 portions adapted to rest on side frames, and flat resilient portions joining the central portion to the end portions.

4. A spring plank for car trucks having a channel shape in cross section in its medial and end 35 portions, the flanges of said channel being cut away inwardly somewhat from the end portions of generally rectangular shape of the spring plank to form flat resilient portions.

5. A spring plank for railway car trucks, comprising a substantially flat metal plate having end 40 portions adapted to rest on the spring seats of said frames, and an intermediate portion integral with said end portions, the portions of the plank where the intermediate portion merges into the 45 end portions being flexible, said intermediate portion being of substantial uniform width throughout and being provided with longitudinal corrugations extending substantially from end portion to end portion of the plank, the opposite side 50 edges of the intermediate portion being substantially parallel and being in horizontal alignment.

6. A spring plank for car trucks having an elongated central rigid portion, end portions adapted to rest on the side frames and resilient 55 portions joining the central portion to the end portions, said end portions being equipped with means for engaging the side frames to prevent other than very limited lateral motion of the spring plank relative to the side frames, said 60 means comprising dowel pin receiving openings provided in said end portions.

RALPH B. WINSHIP.
